H. H. HANGER & J. E. HANGER, JR.

ARTIFICIAL LEG,
APPLICATION FILED DEC. 28, 1916.

1,247,673.

Patented Nov. 27, 1917.

FIG. 1.

FIG. 2.

UNITED STATES PATENT OFFICE.

HENRY HOOVER HANGER AND JAMES E. HANGER, JR., OF WASHINGTON, DISTRICT OF COLUMBIA, ASSIGNEES TO J. E. HANGER, INCORPORATED, A CORPORATION OF THE DISTRICT OF COLUMBIA.

ARTIFICIAL LEG.

1,247,673.

Specification of Letters Patent. Patented Nov. 27, 1917.

Application filed December 28, 1916. Serial No. 139,311.

To all whom it may concern:

Be it known that we, HENRY HOOVER HANGER and JAMES E. HANGER, Jr., citizens of the United States, residing at Washington, in the District of Columbia, have invented certain new and useful Improvements in Artificial Legs, of which the following is a specification.

Our invention relates to artificial legs, and pertains more particularly to the knee joints thereof, and to means for operating same.

The object of our invention is to produce an improved knee joint for artificial legs provided with an operating lever carried within the thigh section adapted to be adjustably secured on the knee bolt to accommodate the comfort and preference of the wearer. Another object of our invention is to produce an operating lever on the knee bolts of artificial legs having means by which the angle of the lever with relation to the vertical axis of the leg may be conveniently and easily changed to modify the action of the lower leg section by the change of leverage thus produced; and a still further object thereof is to produce a more simple, cheap and efficient knee bolt and joint for artificial legs and operating device therefor than has heretofore been attained.

To these ends, our invention includes the combination and arrangement of component parts to be hereinafter described and more particularly pointed out in the claims.

35 In the accompanying drawings, in which like reference characters indicate similar parts;

Figure 1 is a vertical sectional view of the knee joint of an artificial leg provided with our operating lever;

Fig. 2 is a transverse sectional view of the same;

Fig. 3 is a top view of our back check,

Fig. 4 is a vertical sectional view of a modified form thereof, and

Fig. 5 is a vertical sectional view taken on the line 5-5 of Fig. 4.

Referring to the drawings, 1 designates the thigh section of an artificial leg, and 2 indicates the lower leg section which at its upper end fits over the lower end of the thigh section and is pivoted thereto by the knee bolt 3. Both sections are hollow at their adjacent ends to accommodate the operating mechanism to be hereinafter de-

scribed, and the lower end of the thigh section is rounded, and is provided with a vertical central slot 4 in the rear thereof extending from its lower extremity to a point above the knee bolt to receive the back check 5.

The knee bolt 3 is rigidly secured by the clampnut 6 on the lower leg section to permit the operation of the lower leg by the lever arm 8 adjustably secured on the knee bolt.

Said lever arm as shown in Figs. 1 and 2 of the drawings, comprises the arm portion 8', on the inner end of which is provided the split ring 9 adapted to be clamped on the knee bolt 3 by the set screw 10 passing through the lips A on the inner end, while the outer or free end is provided with a grooved wheel 11 over which the suspender 12 is looped. Said wheel is preferably carried on a link 20 pivoted on the outer end of the lever arm to permit the wheel to be folded back when the wearer is in sitting position.

For the purpose of limiting the movement of the lower leg section and for centrally positioning the operating lever 8 thereon, I provide the back-check 5 comprising the bar 5', which at its lower end is secured to the back of the lower leg section while the opposite end is bifurcated at 13 and terminates in a pair of U-shaped yokes 14 which embrace the knee bolt 3 intermediate of its ends.

The lever 8 is preferably positioned between the bifurcated or forked member 14 on the back check 5, by which it is held in a substantially medial position on the bolt.

In the embodiment of our invention shown in Fig. 4 of the drawings, the split ring is clamped back on the arm portion 8' and is clamped on the knee bolt by the set screw 10' passing through the lips A' and the lever arm 8'. The ring and lever thus described are held in adjusted position on the knee bolt by the screw B passing through the ring and bearing against the knee bolt.

It will be understood that a suspender of ordinary form is looped over the wheel 11, by which the lower leg is operated, and it will be further appreciated that the adjustment of the angle of the lever arm relative to the vertical plane of the leg may be had by the screws carried thereon to accommodate same to the comfort and peculiarities of the wearer. Such adjustments may

be conveniently made with a screw driver through the vertical slot 4, and may be made to accelerate the movement of the lower leg section and extend additional tension thereon with the suspender by depressing the outer end of the lever, or may be adjusted to relatively retard the knee action and ease the tension of the suspender by raising the end of the lever, all to accommodate the preference and convenience of the user.

Having thus described our invention, what we claim as new and desire to be secured by Letters Patent, is:

1. In an artificial leg, the combination with a thigh section and a lower leg section, of a knee bolt connecting same rigidly connected with the lower leg section, a laterally extending operating arm adjustably secured on said knee bolt, means for readily altering the angle of said arm with relation to the vertical axis of the leg, and a suspender connected with the free end of said arm, substantially as described.

2. In an artificial leg, the combination with a thigh section and a lower leg section, of a knee bolt connecting same and rigidly connected with the lower leg section, a laterally extending operating arm adjustably clamped on the knee bolt intermediate of its ends, means for readily altering the angle of said arm with relation to the vertical axis of the leg, and a suspender connected with the free end of the lever, substantially as described.

3. In an artificial leg, the combination with a thigh section and a lower leg section, of a knee bolt pivotally connecting same rigidly attached to the lower leg section, a laterally extending operating arm adjustably secured on said knee bolt, a back-check attached to the rear of the lower leg section at its lower end and embracing said knee bolt at its upper end, and a suspender connected with the free end of said operating arm, substantially as described.

4. In an artificial leg, the combination with a thigh section and a lower leg section, of a knee bolt pivotally connecting same rigidly attached to the lower leg section, a laterally extending operating arm adjustably secured on said knee bolt, a back-check attached to the rear of the lower leg section at its lower end and having a forked upper end embracing said knee bolt and the inner end of said operating arm, and a suspender connected with the free outer end of the operating arm, substantially as described.

5. In an artificial leg, the combination with a thigh section and a lower leg section, of a knee bolt pivotally connecting same and rigidly attached to the lower leg section, a laterally extending operating arm adjustably secured to said knee bolt, means for readily altering the angle of said arm with relation to the vertical axis of the leg, a grooved wheel connected with the arm, and a suspender looped over said wheel, substantially as described.

6. In an artificial leg, the combination with a thigh section and a lower leg section, of a knee bolt pivotally connecting same and rigidly attached to the lower leg section, a laterally extending operating arm adjustably secured to said knee bolt, a link pivotally carried on the free end of said arm, a grooved wheel carried on the free end of said link, a bifurcated back-check attached to the rear of the lower leg section at one end and embracing the knee bolt and inner end of said operating arm at its opposite end, and a suspender connected with the wheel on the free end of said link, substantially as described.

7. In an artificial leg, the combination with a thigh section and a lower leg section, of a knee bolt pivotally connecting same and rigidly connected with said lower leg section, a laterally-extending operating arm looped around the knee bolt at its inner end, a set screw for clamping said looped portion on the knee bolt to set the arm at different angles, a wheel carried on the outer free end of the arm, a set screw for adjustably positioning the looped portion on the knee bolt, and a suspender connected with said grooved wheel, substantially as described.

8. In an artificial leg, the combination with a thigh section and a lower leg section, of a knee bolt connecting same and rigidly connected with the lower leg section, a laterally extending arm adjustably secured on said knee bolt at one end, means for readily altering the angle of said arm with relation to the vertical axis of the leg, a link pivotally carried on the free end of said arm, and a suspender connected with the free end of the link, substantially as described.

In testimony whereof we hereby affix our signatures in the presence of two witnesses.

HENRY HOOVER HANGER.

JAMES E. HANGER, JR.
